Since the outer edges of eye members 6 and 12 are angled back out of line with the hook and eye joint, tension on the ends of the belt will tend to pull the central joint of the clasp into this line. But the abutting of shoulders 5 against the face of eye member 16, and the cooperative abutting of the outer edge of eye member 16 on the inner face of tongue 4, provide a stop to keep the clasp from being able to bend in at the center. The inner edges of the shield members also abut to act as further stop means, and thus they also prevent any end play. Thus, tension on the clasp keeps it at one exact position, and rubbing, wearing, squeaking, and scraping are eliminated.

The facts that the belt loop eye portions are bent back and that the clasp is arranged so that it cannot bend back in the center beyond a straight line give the result that there is a bridge 20 between the end loops of the belt, thus holding the tongue 4 and eye portion 16 out from being pressed hard against the body, which would be uncomfortable to the wearer.

The two strips 2 and 10, being fastened together and having the belt fastened to the remaining ends thereof, take the tension direct, and no pull is transmitted through the shields 22, 24. This means that the shields need not be fastened on with so much care and expense, 30 and even if they should fall off, the belt would still be held clasped.

The bends in the three eye members 6, 12, and 16 furthermore impart a small amount of springy "give" to the clasp, which, on occasion, may be 35 just enough to save it from snapping under a heavy strain.

It will be understood that I am not limited to my specific disclosure, which is illustrative only.

I claim:

40 1. In a clasp, a first member having an integral bent back portion near each end and having a transverse slot along one bent back end portion whereby the end of a belt or the like is to be secured by being passed through the slot and 45 looped about the outer frame portion surrounding same, the other bent back end portion of said first member being a tongue and being bent back in the neighborhood of 180°, a second member having an integral portion bent back near 50 each end and having a transverse slot along each bent back end portion, one of said slots being of a size suitable for receiving the tongue on the first member, the other being for securing the second end of the belt or the like in the same 55 manner as the slot for the first end.

2. A belt clasp as defined in claim 1 in which

a first shield member is secured to the face of the first member and a second shield member is secured to the face of the second member, the edges of said shield members abutting when the clasp members are hooked together and the hook and eye joint is spaced to the shield side of the line joining the belt end fastening points.

80 3. A clasp having two separate parts, one of said parts having an end portion bent back, and having a transverse opening along said bent portion, and a tongue on the other of said parts of a width to fit in said opening and doubled back on itself, means for fastening a belt end directly on the ends of the said parts opposite their inter-engaging ends, a shield member fastened to the front face of each of the said parts, said shields and the fastenings therefor being independent of the means for fastening the belt ends to the said parts, said shields being so disposed as to abut each other and act as stops to limit pivotal movement of one part forwardly with respect to the other.

85 4. A clasp consisting of an integral hook member to which one end of a belt is to be fastened, an integral eye member to receive said hook and to which the other end of the belt is to be fastened, points stamped out of each of the hook and the eye members, a shield of softer material than the points fastened to each of the hook and the eye members by having the points driven there- 90 into.

95 5. A clasp comprising a hook member having a narrowed end portion bent back about 180° and spaced slightly from the hook member to form a hook, an enlarged portion at the other 100 end of said hook member having a transverse slot therein to receive an end of a belt and being bent back about 45°, to the same side as the hook, an eye member having an eye portion at one end bent back about 45°, a transverse slot in said eye por- 105 tion of a size to receive the above-mentioned hook, an enlarged portion at its other end bent back about 45° to the same side and having a transverse slot therein to receive the other end 110 of the belt, points struck out from each of said hook member and said eye member to the opposite side from that to which the end portions are bent back, a shield member secured to each of 115 said hook member and said eye member by being driven onto said points, said shield members so spaced as to abut each other when the clasp is 120 coupled and the belt is stretched out.
